US00D973979S

(12) **United States Design Patent** (10) **Patent No.:** **US D973,979 S**
(45) **Date of Patent:** **** Dec. 27, 2022**

(54) **TRAINING COLLAR WITH REMOTE CONTROL**

(71) Applicant: **Shenzhen Yuehuanyu Technology Co., Ltd.**, Shenzhen (CN)

(72) Inventor: **Liping Zhong**, Guangdong Province (CN)

(**) Term: **15 Years**

(21) Appl. No.: **29/814,031**

(22) Filed: **Nov. 3, 2021**

(51) **LOC (13) Cl.** **30-04**

(52) **U.S. Cl.**

USPC **D30/152**; D30/199

(58) **Field of Classification Search**

USPC D30/136-137, 144-145, 151-155, 160, D30/199; D10/104.1, 104.2, 106.1; D11/1-6, 201; D14/137, 144, 155, 188, D14/192, 216-218; D29/100, 101.1, D29/101.2, 101.3, 101.4, 101.5, 124; 119/815, 831-832, 859, 863; 362/104, 362/108

Primary Examiner — Andrew T Nemeth

(57) **CLAIM**

The ornamental design for a training collar with remote control, as shown and described.

DESCRIPTION

FIG. 1 is a front and top perspective view of a training collar with remote control, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures illustrate portions of the training collar with remote control that form no part of the claimed design.

1 Claim, 7 Drawing Sheets
